UNITED STATES PATENT OFFICE.

THOMAS O. SCHRADER, OF ALLENTEWON, PENNSYLVANIA, ASSIGNOR TO THE DENT HARDWARE COMPANY, OF FULLERTON, PENNSYLVANIA, A CORPORATION OF PENNSYLVANIA.

LATCH FOR DOORS.

1,117,709.

Specification of Letters Patent. Patented Nov. 17, 1914.

Application filed August 8, 1914. Serial No. 855,785.

To all whom it may concern:

Be it known that I, THOMAS O. SCHRADER, a citizen of the United States, residing at Allentown, in the county of Lehigh and State of Pennsylvania, have invented certain new and useful Improvements in Latches for Doors, of which the following is a specification.

My invention has relation to a latch for doors, for closing refrigerators, among other uses therefor; and in such connection it relates to the particular constructive arrangement thereof, so that slamming the door fastens the same against release until the pull-handle thereof is operated.

The nature and scope of my present invention will be more fully understood from the following description taken in connection with the accompanying drawings forming part hereof, in which—

Figure 1, is a front elevational view of the latch-fastener for refrigerator and other doors, in an operative position, embodying essential main features of my said invention. Fig. 2, is a side elevational view of one of the members of the latch-fastener. Fig. 3, is a side elevational view of the pull-handle in a position to permit of release of the latch-fastener, to open the door. Fig. 4, is a vertical sectional view through the incased spring controlled shiftable cam of the latch-fastener, showing the tongue or projection of the housing for the pivotal pull-handle in an operative position and also said pull-handle in such position as to permit of the locking of the same. Fig. 5, is a top or plan view; and Fig. 6, is a transverse central sectional view through both members of the said latch-fastener.

Referring to the drawings *a*, is the door with a lock housing *a*¹, applied thereto and having a projection or tongue *a*². The housing is recessed at *a*³, to pivotally support a pull-handle *a*⁴, having a recessed flaring sideways extending finger *a*⁵, and underneath the handle it is provided with an in-turned recessed foot *a*⁶, to engage a keeper *a*⁷, of a shiftable locking means *b*, mounted

in the housing *a*¹. This means is provided with a key turning spindle and stud *a*⁸, for shifting the keeper *a*⁷, into contact with the in-turned recessed foot *a*⁶, of the pull-handle *a*⁴, as clearly shown in Fig. 6, and while the said handle *a*⁴, occupies a vertical depending position, for example, the position as shown in Figs. 1 and 2.

The door-jamb *c*, is provided with a side notched box-like casing *c*¹, for the mounting of a shiftable pivoted cam *c*², therein. This cam is provided with a coiled spring *c*³ which is at one end *c*⁴, connected with the cam and at the opposite end *c*⁵ with the said casing *c*¹, as clearly shown in Fig. 4, so as to normally maintain the said cam in an operative position to be readily shifted against the tension of the spring *c*³, by the tongue or projection *a*², contacting with the said cam by the slamming of the door *a*, causing the said tongue or projection thereby to slip over the surface of said cam to occupy the position in the casing *c*¹, as clearly shown in Fig. 4, thus holding the door securely fastened against release, until the pull-handle is elevated to depress sufficiently the said cam *c*², to enable the tongue or projection *a*², to ride back over the said cam, with the door ajar and with the pull-handle in a vertical depending position. When the latch-fastener occupies the position shown in Fig. 4, in which position the door is fastened against release, the pull-handle will be in a vertical depending position with the recessed foot *a*⁶, of said handle registering with the keeper *a*⁷, of the locking-means *b*, arranged alongside of the pull-handle *a*⁴. Then by turning the key *d*, in the slotted spindle or stud *a*⁸, of the locking-means *b*, the keeper *a*⁷ thereof, will be shifted into contact with the recessed foot *a*⁶ of the said pull-handle to prevent further movement thereof.

Having thus described the nature and objects of my invention, what I claim as new and desire to secure by Letters Patent is—

A latch-fastener for doors, comprising a housing having a tongue and a pivotally

supported pull-handle having a finger, a spring controlled shifttable cam mounted in a casing of the door-jamb and arranged to be actuated by said tongue to latch said door and by said finger through the actuation of said handle to release said door.

In witness whereof I have hereunto set my

signature in the presence of two subscribing witnesses.

THOMAS O. SCHRADER.
